DESIGN FOR A BLOUSE

Della Showers, Long Island, N. Y.

Application January 12, 1938, Serial No. 74,221

Term of patent 3½ years

To all whom it may concern:

Be it known that I, Della Showers, a citizen of the United States, residing at Long Island, in the county of Queens and State of New York, have invented a new, original, and ornamental Design for a Blouse, of which the following is a specification, reference being had to the accompanying drawing, forming part thereof, wherein—

I claim:

The ornamental design for a blouse substantially as shown.

DELLA SHOWERS,
